UNITED STATES PATENT OFFICE.

GEORGE A. BIRKENHEAD, OF VANCOUVER, BRITISH COLUMBIA, CANADA.

PARLOR GAME.

1,331,741.

Specification of Letters Patent. Patented Feb. 24, 1920.

Application filed May 21, 1919. Serial No. 298,681.

To all whom it may concern:

Be it known that I, GEORGE A. BIRKENHEAD, a citizen of the Dominion of Canada, residing at Vancouver, in the Province of 5 British Columbia, Canada, have invented certain new and useful Improvements in Parlor Games, of which the following is a specification.

This invention relates to an improved 10 parlor game of that class wherein a relatively small sized ball is driven either with the fingers or by a cue at another ball located adjacent an obstructing barrier in which is a series of pockets, the object of 15 the player being to locate one or both balls in any of the pockets, to which different values are assigned.

The invention is particularly designed to 20 provide the wherewithal for a game of this kind without the requirement of a cumbersome and somewhat expensive board or special table.

The barrier with this object in view is composed of three short pieces dovetailed together 25 that they may readily be put together on any suitable existing table or on the floor of a room.

The invention is fully set forth in the following specification, reference being 30 made to the drawing by which it is accompanied, which represents the device in perspective as arranged for play.

My improved game apparatus comprises 35 three short pieces of wood, a middle piece 2 and two end pieces 3—3, the latter being projected at approximately 145 degrees from the said middle piece 2.

The abutting ends of the pieces 2 and 3 are adapted for being readily jointed together 40 by dove-tailed tongue and groove connections 4, and in such manner that the whole frame, the ends 3—3 and the middle pieces 2, will retain their connection under the impact of balls that engage therewith,

45 as will presently more fully appear. Along the inner edges of the pieces 2 and 3—3 is a series of circular pockets 5, each having a relatively restricted inlet or throat and the series of circular pockets are relatively so 50 arranged that they radiate from and are consequently spaced an equal distance from a spotting point from which the player spots the ball or marble to be projected into any of the pockets in the members 2 and 3—3.

55 It will be readily apparent from the drawings that by forming the pieces 2 and

3—3 and connecting them in the manner shown and described, a central series of pockets 1, is provided which, in practice, have minor values, say 5 and 10, since the 60 said pockets are disposed in a more direct line with the spot ball 6, and the opposite side pockets 3—3 have the major values, say 15, 20, 25, since more skill is required to direct the spot ball into the opposite side 65 pockets than is necessary when projecting the spot ball in the transversely disposed pockets on the middle piece 2.

In playing my improved game the members 2, 3—3 being connected, as shown, the 70 ball to be played is spotted at 6 and each player impels his spot ball at 6 from a balk line at 7 that extends at right angles to the series of minor pockets 10, 5, 10 and skillfully directs the balk line or marble to so 75 impact the spot ball or marble to cause it to move toward the members 2, 3—3, it being understood that considerable more skill is required for driving the spot ball into the major value pockets 15, 20, 25 than is required to drive the spot ball into the straight 80 ahead pockets 10, 5, 10.

The device is extremely simple and cheap to manufacture and for that reason has advantages over parlor games of this character 85 which are frequently unnecessarily expensive, and are cumbersome and clumsy both for transport and for disposing in the house. The parts can be quickly put together on a table of ordinary size, or, if preferred, on 90 the floor and the game may be played with glass marbles of suitable size to pass through the inlets to the pockets, or, if, as is frequently the case, the noise of such glass marbles is considered objectionable, small 95 rubber balls may be used.

Having now particularly described my invention, I hereby declare that what I claim as new and desire to be protected in by Letters Patent, is:

1. A game appliance of the character described comprising three members each having a series of like shaped pockets in the inner face, the said three members including a central member and opposite end members, 105 the said end members being projected inwardly at approximately 145 degrees with respect to the central member, the meeting faces of the said central and end members radiating from a common center that constitutes the spot from which a ball may be 110 impelled toward the pockets.

2. A game appliance of the character stated, comprising a ball receiving space including a central member having a series of pockets on the inner edge, an end member projected from each end of the central member and extending inwardly from the said central member at approximately 145 degrees with respect to the said central member, a series of pockets, each of which includes a restricted throat or passage located

10 along the inner edges of the center and end members, all of the said pockets being substantially at an equal distance from a common point that constitutes the spot from which the ball is to be impelled toward 15 the pocket edges of the central and the end members.

In testimony whereof I affix my signature.

GEORGE A. BIRKENHEAD.
